UNITED STATES PATENT OFFICE.

JOHN HOPE, OF LIVERPOOL, COUNTY OF LANCASTER, ENGLAND.

GAME-COUNTER.

SPECIFICATION forming part of Letters Patent No. 400,770, dated April 2, 1889.

Application filed October 16, 1888. Serial No. 288,201. (No model.)

To all whom it may concern:

Be it known that I, JOHN HOPE, engineer, a subject of the Queen of Great Britain, and a resident of 14 Water Street, Liverpool, in 5 the county of Lancaster, England, have invented new and useful Improvements in Apparatus for Marking or Registering the Scores Made in Playing the Game of Billiards and other Like or Equivalent Games, of which the 10 following is a specification.

This invention relates to that type of marking or registering apparatus in which the marking is effected through mechanical devices and the number of games played is registered 15 by a counter, and in which two sets of marking devices are employed, the score of one player or set of players being registered by one of the marking devices and the score of another player or set of players being registered 20 by the other marking device.

The chief objects of my invention are to make markers of the kind just specified more durable, simpler, and more effective for the 25 purposes for which they are intended, and to render it possible at the same time to construct the improved apparatus at a lower cost than heretofore.

The following is a description of an apparatus, according to my invention, for marking 30 the scores made in playing the game of billiards and pyramids, reference being had to the annexed sheets of drawings, which make a part of this specification, and to the letters and figures of reference marked thereon, like 35 letters and figures being used to denote like parts throughout the drawings.

The drawings, together with the description hereinafter given, will be sufficient to enable others skilled in the art to which my invention 40 belongs to make and use the same.

In the drawings, Figure 1 is a front elevation of an apparatus according to my invention. Fig. 2 is a back elevation of the apparatus, showing the internal arrangement of the 45 mechanism, the back of the apparatus being removed. Fig. 3 is a sectional end elevation of the apparatus, taken through x x , Fig. 1. Fig. 4 is a front view showing the marking of the back dial.

50 In apparatus involving my invention there

are employed a case or frame, circular dials, pointers working about the axis of the dials, a locking device, a counter for registering the number of games played, and a sounding device for denoting the termination or commencement of every fresh game.

The apparatus shown in the drawings is an example of a billiard-marker embodying all the above-named features and parts, and of a type especially applicable for use in public 60 billiard-rooms or places where they would be used under similar conditions. The apparatus comprises an external arrangement of dials, pointers, and a counter or register for scoring 65 the games of billiards and pyramids, and an internal arrangement of mechanism for operating the parts.

a is the case or frame of the apparatus, in which are mounted two circular marking-dials, one for each player or set of players. 70 These dials are in duplex and of the same construction. It will therefore be sufficient to describe one. It consists of a front dial, b , and a back dial, c , the front dial, b , being provided with apertures or windows d , and the edge b' of the dial divided into fifty divisions, which are partly provided with figures, 75 say from one to thirty, in numerical order, from right to left, for marking the game of billiards. The center, b^2 , of the dial is provided with sixteen divisions, numbered 0, 1, to 15, for marking the game of pyramids.

The under or back dial, c , is provided with two sets of numerals divided into twenty divisions and arranged thus—5, 60, 10, 65, 15, 80 70, 20, 75, 25, 80, 30, 85, 35, 90, 40, 95, 45, 100, 50, 55. This dial is arranged on its axis so that it can be set by the shunt-piece e to exhibit either one or the other set of the above figures through the windows d .

In the drawings, Fig. 1, the dials are shown exhibiting like sets of figures. I employ two pointers, h i , the pointer i being used to mark each "break" or score, and which I call the "break-pointer," while the other pointer, h , 95 is moved by the break-pointer i in such a manner that it (the game-pointer) will be moved forward the exact number of points traversed by the break-pointer. Thus when registering a score the break-pointer i , whose 100

normal position is zero, is moved to the left to the number on the dial edge b' representing the score or break made by a player, and is then returned to zero, in which latter movement the game-pointer h is moved forward to the correct number. By this means each increment of score is added to the total without the necessity of the mental operation of arithmetical addition. I make the game-pointer h larger and heavier than the break-pointer i , so as to clearly indicate the progress of the game. I also fine the game-pointer down in line with and to serve to point to the "pyramid figures" in the center b^2 , to be used when playing the game of pyramids. The break-pointer i is made lighter and less discernible, as its purpose is simply to feed the pointer h . The dials a and c are surrounded by a bezel, j , holding a glass cover perforated in the center to permit of the projection of a spindle and milled head from the mechanism herein-after described. I prefer to make the dial b of decorated tinned sheet-iron plates. I turn up the edge of the front dial, b , to form a rim to give it strength and to support the glass cover. I also turn up the edge of the back dial, c , about one-sixteenth of an inch to prevent undue attrition between the two dials, whereby the numerals on the dial c would be defaced.

The spindle h' , on which the game-pointer h is carried, is hollow, and on its inner end there is provided a toothed wheel, l , provided with fifty teeth, corresponding with the divisions at b' on the edge of the dial b .

The break-pointer i is carried by a solid spindle, i' , which passes through the hollow spindle h' of the game-pointer h , and this spindle i' passes through the glass cover and is provided with a milled head, k , whereby it (the break-pointer) is moved.

On the inner end of the spindle i' is fixed an arm, m , which is provided with a pawl, n , by which the toothed wheel l is worked, and thereby, through the hollow spindle h' , the game-pointer h is moved.

p is a foundation-plate fixed to the frame a and which carries the principal parts of the mechanism. This plate p is provided with bosses to support the hollow spindles h' , and thereby the solid spindles i' of the break-pointers i of the two dials b .

q is a locking-plate. It is actuated by a key, o , which is inserted in the front of the apparatus. The plate q is pivoted on the plate p in its center, above the key o , and works in guides r , and is held in its normal position (that is, locking the arms m) by a spring, s , so that the arms m and the spindles i' and break-pointers i cannot be moved until the apparatus is unlocked by the key o , lifting and retaining the plate q out of gear with the arms m .

t is a bell-crank lever, the short arm t' of which is actuated by a cam, u , on one of the wheels l , as shown in the drawings. The long

arm t^2 of the lever t carries a pawl, v , and this pawl v communicates motion to the counter device w . This counter device w is of any well-known kind and does not need a detailed description. The back action of the lever t is provided by the spring t^3 .

Attached to the lever t is a hammer, x , which, when a game is completed and the counter w moved, strikes a gong, y , and gives notice that the game is ended.

I construct the frame a in such a manner that it cannot be entered clandestinely. The back or cover a' is arranged to slide in grooves 1, and a block, 2, is then fixed so that it cannot be withdrawn, the block 2 being fixed by a screw, 4, the head of which is in the front of the frame a . The screw-head is countersunk, made level, and then covered by a seal, 3, or by gumming a special label over it. It will thus be seen that the back of the machine cannot be removed without withdrawing the screw, and in doing this the seal or label will be destroyed and the attempt to enter the machine discovered.

I prefer to use that kind of game pointer or register w in which the numbers are impressed on flat disks, and in order that it cannot be tampered with from the outside I place it and the glass that covers it wholly within the frame a . On the outside of the frame a , I fix a metal plate, z , having three projections on the back equal in length to the thickness of the front of the frame a , and through each of these projections I make a conical hole of the smallest possible size, through which the indications of the register can be observed.

The operation of marking a game of billiards by an apparatus according to my invention is as follows: The dials c are set by the shunt-pieces e to exhibit 5, 10, 15, and so on to 50. When a break is made, the pointer i is moved to the left by the milled head k to the number representing the break on the divisions on the edge b' of the dial b . In this act of moving the break-pointer i its spindle i' moves the arm m , so that the pawl n engages with a tooth of the wheel l corresponding to the number on the edge b' of the dial b to which the pointer i has been moved. The pointer i is now returned to its zero position, and in the act of returning the wheel l is moved, and thereby, through the hollow spindle h' , the game-pointer h is moved and indicates on the dial the same amount as was indicated by the break-pointer i . This action is repeated for each break, and the successive breaks are thus mechanically added to the score indicated by the game-pointer h without the necessity of mental addition. At the end of each game of fifty, or when the pointer h reaches 50, the counter w is advanced a unit, and the gong y is sounded. When the game is a "one hundred up," after the score of fifty has been reached the dials c are moved by the shunt-pieces e to exhibit the

higher order of numbers—namely, 55, 60, 65, and so on to 100—and the marking continued as before.

What I claim as my invention, and desire to 5 secure by Letters Patent, is—

1. In a billiard and other register, the combination, with a dial provided with numerals, a main working-pointer for registering the state of the games, a single ratchet-wheel 10 mounted on said pointer, and a pawl-lever and pawl by which said wheel is actuated, of a hand-actuated pointer mounted on the same arbor as the main working-pointer and connected with said pawl-lever, whereby the increments of score are added and the said main working-pointer operated, substantially as described.

2. The combination, with the pointer-spindle *i'* of an apparatus for marking the scores 20 made in playing the game of billiards and other like games, of a cam, *u*, lever *t*, secondary counter *w*, gong *y*, and gong-striker *x*, said lever being adapted to be operated by the said cam and to actuate the said counter 25 and gong, as set forth.

3. In a billiard or other game marker, the combination of the spindle *i'*, the actuating-head *k*, pointer *i*, pawl-lever *m*, pawl *n*, ratchet-wheel *l*, hollow shaft *h'*, pointer *h*, a numeral-dial, *c*, and the cam *u*, lever *t*, gong *y*, 30 striker *x*, pawl *v*, and counter *w*, as set forth.

4. The combination, with the actuating pawl-levers *m*, of a lever, *q*, and key *o*, said lever being adapted to engage and interlock with the said pawl-levers *m* and operated by 35 the key *o*, substantially as and for the purposes set forth.

5. In a billiard or other game marker, the combination of the spindles *i' i'*, actuating-heads *k k*, pointers *i i*, pawl-levers *m m*, 40 pawls *n n*, ratchet-wheels *l l*, hollow shafts *h' h'*, pointers *h h*, cam *u*, lever *t*, gong *y*, striker *x*, pawl *v*, counter *w*, and a locking-lever, *q*, and key *o*, substantially as and for the purposes set forth.

JOHN HOPE.
